UNITED STATES PATENT OFFICE.

FRANK YOUNGER, OF WALLACE, CALIFORNIA, ASSIGNOR OF FIFTEEN ONE-HUNDREDTHS TO JOE CALCATERRA, OF WALLACE, CALIFORNIA.

SANITARY DISPENSING APPARATUS.

1,303,141.

Specification of Letters Patent.

Patented May 6, 1919.

Application filed December 28, 1917. Serial No. 209,463.

To all whom it may concern:

Be it known that I, FRANK YOUNGER, a declarant citizen of the United States, with first papers, but subject of Emperor of Germany, residing at Wallace, in the county of Calaveras and State of California, have invented certain new and useful Improvements in Sanitary Dispensing Apparatus, of which the following is a specification.

10 These improvements have to do with that general type of dispensing apparatus disclosed in my co-pending application Serial Number 175,438, filed June 18, 1917, and have as their primary object to provide a 15 construction by means of which to adequately control the discharge of the contents of the apparatus so as to obtain a predetermined quantity of said contents. It is further comprehended as a feature of the 20 discharge means utilized in said apparatus that by proper manipulation thereof either a relatively small or relatively large amount of the material to be dispensed may be had at the will of the operator, this result being 25 accomplished by the special arrangement of the valve instrumentalities forming a part of the discharge means above referred to.

With the above and other objects in view, the invention consists in the construction, 30 combination and arrangement of parts all as hereinafter more fully described, claimed and illustrated in the accompanying drawings, wherein:

Figure 1 is a vertical sectional view 35 through an apparatus constructed in accordance with my present invention;

Fig. 2 is a side elevation of the device, a portion of the upper part of the apparatus being broken away and shown in section 40 and the manipulating elements for the discharge means being removed as when it is desired to fill the receptacle;

Figs. 3 and 4 are sectional views on the lines 3—3 and 4—4 respectively of Fig. 1;

Fig. 5 is a sectional view of the manipulating heads for the discharge means;

Fig. 6 is an enlarged sectional view of the discharge means, the manipulating elements therefor being omitted;

Fig. 7 is a sectional view on the line 7—7 of Fig. 1; and

Figs. 8 and 9 are sectional views of the base portions of the apparatus.

Throughout the following detail description, and on the several figures of the draw-

ings, similar parts are referred to by like reference characters.

Referring to the drawings, 1 indicates the main body portion of the dispensing apparatus forming the subject matter of this invention, preferably of glass material and provided at its lower periphery with protuberances 2 for interlocking with the base section of the device. The base portion consists of the upper part 3 on which the globe 1 is mounted and the standing portion 4 in which the upper section 3 is received. The lower portion of said upper section terminates in a funnel shaped passage 5 leading from the intermediate constricted 60 throat portion 6 to the closed bottom 7 in which is provided a central opening 8. The material to be dispensed, for instance sugar, is contained in the globe portion 1 and the upper portion 3 of the base section and is 65 retained in such container by discharge means now to be set forth.

The means by which control of the dispensing of the contents of the apparatus is attained, consists of the discharge valve 9 80 which normally occupies a position at the lower portion of the throat 6, the cut-off valve 10 arranged above said discharge valve and in spaced relation thereto, together with actuating means for these parts. It will be observed that the valves 9 and 10 are frusto-conical in formation, the discharge valve being carried by the rod 11 seated at its lower end in a spider 12 and carrying at its lower portion a spring 13 85 which lies intermediate the spider and the discharge valve and holds this part of the discharge means in its normal position closing the throat or discharge opening. The valve 10 is carried by the lower extremity of the tube 14 in which the rod 11 is disposed and a spring 15 lies intermediate the discharge valve 9 and the cut-off valve 10 holding these parts in their relative positions under normal conditions.

This spring 15 is partially compressed normally so that when the discharge valve is moved relatively to the cut-off valve as will later appear, sufficient tension is still possessed by said spring to retain the cut-off valve against movement by virtue of the weight of the contents of the receptacle resting thereupon. Adjacent to the upper end the rod 11 has a pin 16 which projects into aligned slots 14' in the outer tube 14. 100

110

The upper end of the tube 14 is provided with the sleeve 17 which projects through the upper end of the globe 1 and constitutes the filling opening for the receptacle. As 5 will be noted in Fig. 5 a head 18 is provided, said head having an annular flange 19 which rests upon the upper edge of the sleeve 17, said head furthermore having a short plunger 20 extending thereinto and 10 coöperating with or resting upon the upper extremity of the rod 11.

Describing the operation of this apparatus, the operator disposes the dispensing apparatus upon the receptacle into which the 15 contents of the dispensing apparatus is to be discharged, such for instance as the cup 21 shown in dotted lines in Fig. 1. The discharge means is now operated according to the quantity of sugar which is desired. 20 Assuming, for example, that a small predetermined quantity is desired, the fingers grasp the head 18 and press the same downwardly. Owing to the pin and slot connection, both the discharge valve 9 and the 25 cut-off valve 10 will be depressed, the former passing slightly out of the throat 6 and the latter cutting off the supply from the throat 6 simultaneously, so that the material which has gravitated into position between these valves is discharged into the 30 cup through the funnel passage 5. This quantity which has been discharged may be a spoonful quantity.

Assuming, further, for example, that the 35 operator wishes a larger quantity than that just referred to, instead of directly manipulating the discharge means in the manner just described, a finger is placed upon the short plunger 20 and the rod 11 depressed 40 so as to move the discharge valve 9 downwardly in the throat 6 to its lowermost position in this portion or passage. The contents of the receptacle will naturally follow the movement of the lower valve and therefore 45 a greater quantity of such contents will be introduced between the valves 9 and 10 in an obvious manner. At this point the pin 16 will reach the bottom of the slots 14', whereupon both the rod 11 and the tube 14 50 will be actuated and the two valves 9 and 10 moved downwardly, the latter cutting off the supply of the sugar as the former passes from the throat and discharges the larger quantity of the commodity into the receptacle arranged beneath the apparatus to receive the same.

It will thus be apparent that the actuating means forming a part of the discharge instrumentalities have independent and joint action such that one of the valve members may be moved relatively to the other or both moved simultaneously, according to the quantity of the material contained by the apparatus that is desired.

65 I preferably arrange the springs for re-

taining the relatively movable parts of the discharge means in their normal positions at the points shown in the drawings because they are there protected by the shedding action of the valves with which they coöperate.

When it is desired to fill the receptacle 1 the actuating head 18 which constitutes a stopper or closing means for the filling opening is removed and the short plunger 75 20 is detachable therewith. It is obvious, however, that slight changes may be made in the arrangement of parts as hereinbefore described without departing from the spirit of the invention and within the scope of the 80 appended claims.

Having thus described the invention, what I claim as new is:

1. In dispensing apparatus of the class described, the combination with a receptacle 85 having a discharge outlet, of discharge means for delivering the contents of the receptacle in predetermined quantities including spaced valves one movable relatively to the other or both movable simultaneously 90 in effecting discharge action, according to whether a relatively smaller or larger quantity of the contents is to be delivered, and means for operating either of the valves aforesaid.

2. In dispensing apparatus of the class described, the combination with a receptacle having a discharge passage, of discharge means for delivering the contents of the receptacle in predetermined quantities including spaced valves arranged at the discharge passage so as to receive a predetermined quantity of the contents of the receptacle between said valves, one of said valves being movable preliminarily to discharge action along the passage to increase the holding capacity between the valves, the other of said valves being thereupon movable with the first mentioned valve to effect discharge of said predetermined quantity, and separate actuating means connected to each of said valves.

3. In dispensing apparatus of the class described, a receptacle having a discharge outlet, and discharge means including a discharge valve normally closing the discharge outlet, a cut-off valve adapted to coöperate with the outlet to limit the quantity discharged and spaced from the discharge valve, and means for actuating either or 115 both of said valves.

4. In dispensing apparatus of the class described, a receptacle having a discharge outlet, discharge means comprising relatively movable parts, actuating means for 125 each part and a connection intermediate said parts whereby to actuate one part from the actuating means for the other part or to actuate both parts from one actuating means.

5. In dispensing apparatus of the class described, a receptacle having a discharge outlet, and discharge means comprising spaced frusto-conical valves coöperative with the discharge outlet, and spring retaining means for holding the valves in normal spaced relation and arranged to be protected from the contents of the receptacle by the valves aforesaid.
- 10 6. In dispensing apparatus of the class described, a receptacle having a discharge outlet at one end and a filling opening at the other, discharge means for controlling the quantity of the contents of said receptacle 15 to be discharged, and actuating means therefore including a manipulative head constituting a closure for the filling opening.
7. In dispensing apparatus of the class described, a receptacle having a discharge outlet at one end and a filling opening at the other, discharge means for controlling the quantity of the contents of said receptacle 20
- to be discharged comprising spaced valves coöperative with the discharge opening, rod members carrying said valves extending 25 through the filling opening, and an actuating head comprising relatively movable parts adapted to actuate the rod members aforesaid.
8. In dispensing apparatus of the class 30 described, a receptacle having a discharge outlet at one end and a filling opening at the other, and discharge means for controlling the quantity of the contents of said receptacle to be discharged comprising spaced 35 valve members coöperative with the discharge opening, rod members carried by said valves, an interlocking connection between the rod members permitting relative movement of the latter and manipulative means 40 at the filling opening for actuating one or both of said rod members.

In testimony whereof I affix my signature.
FRANK YOUNGER.
